JULIO H. RAE, OF SYRACUSE, NEW YORK.

Letters Patent No. 86,249, dated January 26, 1869.

IMPROVED ORE-WASHER AND SEPARATOR

The Schedule referred to in these Letters Patent and making part of the same.

To all whom it may concern:

Be it known that I, JULIO H. RAE, of Syracuse, in the county of Onondaga, State of New York, have invented a new and improved Ore-Washer and Separator; and I do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a sectional plan or top view thereof.

Similar letters indicate corresponding parts.

This invention consists in the arrangement of one or more separators, each separator being placed into a shallow pan, and provided with a perforated hollow globe or rose, which connects with a pipe containing water, under pressure, in such a manner that, by admitting the pulp into the separator, the light parts are separated from the heavier parts, and driven up, and caused to flow over the edge of the separator into the pan, while the heavy parts settle down and collect on the bottom of the separator; and, by these means, for instance, the quicksilver generally used in treating auriferous ores can be readily separated from the pulp with which the same is mixed.

The letter A represents a tank, which serves to receive the pulp, such as the tailings, flowing from an amalgamator, or, if desired, a pulp composed of ground ore and water.

In this vessel, the pulp is agitated by a series of beaters B, which extend from a vertical shaft, C, and it is allowed to discharge from said vessel through a spout, a, into a washer or separator, D.

This separator is placed in a pan, E, and it is provided with a perforated hollow globe or rose, F, which

connects with a pipe, G, containing water under pressure.

When the pulp begins to flow into the separator, water is admitted into the perforated globe, and the jets of water issuing from the perforations of said globe meet the current of the pulp, and serve to separate the lighter from the heavier parts, so that those parts of the pulp which have the greatest specific gravity will precipitate to the bottom of the separator, while the light parts are caused to flow off, over the edge thereof, and collect in the pan E.

From this pan extends a spout, d, over a second separator, H, in which the pulp escaping from said pan is exposed to another separating-operation, and so on until the separation of the various parts of the pulp has been carried on to the desired degree.

By these means, I am enabled to separate and save from the tailings of an amalgamator a large percentage of quicksilver, which is now lost, and the expense of the amalgamating-process is materially reduced.

My apparatus can, however, also be used with advantage for separating the precious metals from the ores containing the same, or, in fact, for separating bodies of different specific gravity.

Having thus described my invention,

What I claim as new, and desire to secure by Letters Patent, is—

The arrangement of one or more separators D, each placed in a pan, E, and provided with a perforated hollow globe or rose, F, which is supplied with water under pressure, substantially in the manner and for the purpose set forth.

JULIO H. RAE.
